UNITED STATES PATENT OFFICE

ROBERT SANFORD RILEY AND JAMES H. MCELROY, OF WORCESTER, MASSACHUSETTS,
ASSIGNORS TO RILEY STOKER CORPORATION, OF WORCESTER, MASSACHUSETTS, A
CORPORATION OF MASSACHUSETTS

UNDERFEED STOKER

Application filed September 18, 1920. Serial No. 411,051.

This invention relates to an underfeed stoker of the usual type in which coal is fed into the front or outer end of one or more separate retorts. Such stokers are more commonly used for burning soft or bituminous coal and are then operated on the underfeed system, the coal being gradually forced upward from the bottom of the retort and the fuel bed being replenished from below instead of above.

It is sometimes found necessary or desirable to utilize such underfeed stokers for burning harder grades of fuel such as anthracite coal. Under these conditions it may be found desirable to change the operation of the stoker from the distillation system of combustion to the overfeed system of combustion.

It is the general object of our invention to provide a construction by which an underfeed stoker may be thus changed for overfeed combustion, with a minimum expenditure of time or labor.

With this general object in view an important feature of our invention consists in the provision of a removable overfeed grate adapted to be secured within an underfeed retort of the usual type.

Other features of our invention relate to the provision of means for controlling the supply of air to such an overfeed grate, and to means for reciprocating the grate longitudinally when found desirable.

Our invention further relates to arrangements and combinations of parts which will be hereinafter described and more particularly pointed out in the appended claims.

A preferred form of our invention is shown in the drawings in which

Fig. 1 is a longitudinal vertical sectional elevation of a stoker with parts at the front and rear shown diagrammatically having our improvements embodied therein;

Fig. 2 is an enlarged sectional elevation of the auxiliary grate showing also certain parts of the stoker adjacent thereto;

Fig. 3 is a transverse sectional elevation taken along the line 3-3 in Fig 2;

Fig. 4 is a detail sectional view to be described, and

Fig. 5 is a sectional plan view of certain actuating mechanism.

Referring to the drawings we have shown a section of an underfeed stoker of a common type, having a front wall 10, a rear wall 11, a feed hopper 12, a ram 13 for forcing the coal from the hopper to the retort, a crank-shaft 14 for reciprocating the ram 13, and driving mechanism 15 connected through a gear box 16 to drive the crankshaft 14. At the rear of the retort a rocking discharge plate 17 assists the rearward movement of the ash and waste to the discharge opening 18. The chamber 19 beneath the retorts is enclosed at the sides and is adapted to contain air under pressure.

Each retort preferably comprises a bottom plate 20 (Fig. 3) and side walls 21 provided with air admitting openings 22 and commonly movable longitudinally by driving connections of the usual commercial type such as are shown for instance in the applicant Riley's prior Patent No. 1,090,651, issued March 17, 1914.

Such driving connections are indicated in Fig. 5, which shows the coal-feeding ram 13 provided with a cross-bar 40 having openings in its opposite ends through which threaded rods 41 are freely slidable. These rods 41 are secured in slidably mounted members 42, which in turn are directly secured to the movable side walls 21.

The rods 41 are provided with heads 43 adapted to be engaged by one side of the cross-bar 40, and with nuts 44 adapted to be engaged by the opposite side of the cross-bar as the ram is reciprocated.

The side walls 21 thus have a lost motion connection with the coal-feeding ram and partake of the motion of the ram during any desired portion of such motion. The extent of motion of the side walls may be adjusted by turning the rods 41 in the slidably mounted members 42 or by adjusting the nuts 44 on the rods 41.

The parts thus far described are of the usual type and comprise no part of our present invention.

In order to convert an underfeed stoker for overfeed combustion, we provide an overfeed grate member 23 preferably of the general

appearance shown in Figs. 2 and 3. The front end of the grate member is formed as a closed plate 24 and the opposite end of the member is constructed to act as an overfeed grate surface, and for this purpose is provided with air openings 25. The grate member is also provided with side walls 26 connected by cross bars 27 through which extend bolts 28 by which the grate member is secured to the bottom plate 20. Air openings 29 are formed in the bottom plate 20 so that air may pass from the air chamber 19 to the openings 25 in the grate member. When the grate member 23 is removed and the stoker is operated as an underfeed stoker, the air openings 29 may be closed by suitable cover plates 30 as shown in Fig. 4.

It is sometimes desirable to reciprocate the grate member 23, and with this in view the bolts 28 extend through slots in the bottom plate 20. When the member 23 is to be reciprocated the bolts 28 may be loosened sufficiently to permit such relative movement.

Any suitable mechanism may be provided for reciprocating the member 23. In the drawings we have shown a rod 30 bolted to the end 24 of the member 23 and having its outer end extending through an opening in the ram 13. Nuts 31 adjustable on the rod 30 are engaged by the ram 13 as it moves backward and forward, and a reduced intermittent motion is thus conveyed to the member 23.

Having thus described our invention, the operation and advantages thereof will be readily apparent. For distillation combustion the stoker is operated as usual, the air openings 29 being suitably closed. For overfeed combustion the grate member 23 is placed in the retort and is secured to the bottom plate by bolts 28. If it is found desirable to reciprocate the member 23, the bolts 28 are loosened and the nuts 31 are suitably adjusted on the rod 30. The stoker may be thus readily adapted to the fuel available.

Having thus described our invention it will be evident that changes and modification can be made therein by those skilled in the art within the spirit and scope of our invention as set forth in the claims, and we do not wish to be otherwise limited to the details herein disclosed, but what we claim is:—

1. In an underfeed stoker, an underfeed retort, a grate member movable longitudinally in said retort and effective to elevate the fuel by forward movement thereof, and means to reciprocate said grate member in said retort, said grate member having provision for conducting air therethrough to fuel in said retort.

2. In an underfeed stoker, an underfeed retort, a grate member movable longitudinally in said retort and effective to elevate the fuel by forward movement thereof and to

feed the fuel rearward by rearward movement thereof, and means to reciprocate said grate member in said retort, said grate member having provision for conducting air therethrough to fuel in said retort.

3. In an underfeed stoker, in combination, an underfeed retort, a movable grate member effective to supply air for combustion of fuel in said retort, and means to move said grate member, the fuel capacity of said retort remaining the same for every operative position of said grate member.

4. In an underfeed stoker, in combination, an underfeed retort, a movable grate member disposed entirely within said retort and effective to supply air for combustion of fuel in said retort, means to admit air beneath said grate member, and means to move said grate member longitudinally in said retort.

5. In an underfeed stoker, in combination, an underfeed retort having a bottom plate, a movable grate member located entirely within said retort above said bottom plate and effective to supply air for combustion of fuel in said retort, means to slidably secure said grate member on said bottom plate within said retort, and means to reciprocate said grate member.

6. In an underfeed stoker, in combination, an underfeed retort, a movable grate member effective to supply air for combustion of fuel in said retort throughout a major portion of the length of said retort, means to slidably support said grate member in said retort, a fuel feeding ram for said retort, driving mechanism therefor, and a lost motion connection between said ram and said grate member.

7. In an underfeed stoker, in combination, an underfeed retort having side walls provided with tuyère openings, a ram to move the fuel rearward in the retort and a grate member in said retort effective to supply air to the fuel in said retort throughout a major portion of the length of said retort, said grate member being of substantially the width of the retort and having an upwardly and rearwardly inclined front surface effective to elevate the fuel in the retort as said fuel is moved rearward relative to said grate member.

8. A furnace having, in combination, a downwardly and rearwardly inclined fuel retort having side walls longitudinally movable, tuyère structures mounted on said side walls, means for reciprocating said side walls longitudinally and for feeding the fuel into the forward end of the retort, and a tuyère structure mounted on the inclined bottom wall of the retort of substantially the width of and extending substantially the length of the retort for supplying air to the fuel throughout substantially the area of the retort.

9. An underfeed stoker having tuyères mounted upon the side walls of the underfeed

retorts through which the main supply of air is admitted to the fuel bed, supplementary air admission means located within each retort between the side walls thereof for admitting a supply of air into the portions of the fuel bed situated over the centers of the retorts and at various points along the length thereof, means for moving said supplementary air admission means, and means for moving the side walls so as to assist in slicing and advancing the fuel bed.

10. An underfeed stoker comprising movable side walls, air admission means carried by said moving side walls, supplementary air admission means located within each underfeed retort between the movable side walls thereof, for agitating and breaking up the fuel as it is advanced down the retort, means for moving said supplementary air admission means so that said supplementary air admission means serve both to admit a supply of air into the portions of the fuel bed positioned over the center of each retort so as to aerate the fuel and simultaneously to cool and prevent burning out of the air admission and agitating means.

11. In an underfeed stoker, an underfeed retort having side walls, tuyère structures mounted on said side walls, a ram to move the fuel rearwardly in the retort, and a grate member between the retort walls which is of substantially the width of the retort and extends substantially the length thereof, said grate member having tuyère openings effective to supply air to the fuel in said retort throughout substantially the entire area of the retort.

12. In an underfeed stoker, an underfeed retort having side walls provided with tuyère openings, a ram to move the fuel rearwardly in the retort, and a fuel supporting grate member between the retort walls which is of substantially the width of the retort and extends throughout the major portion of the length thereof, said grate member having a downwardly and rearwardly sloping face extending the major portion of its length and having rearwardly directed tuyère openings throughout its entire rearwardly sloping face effective to supply air to the fuel in said retort.

In testimony whereof we have hereunto affixed our signatures.

ROBERT SANFORD RILEY.

55 JAMES H. McELROY.
